UNITED STATES PATENT OFFICE

2,288,730

FLEXIBLE NOZZLE

Russell K. Nash, Brookline, Mass., assignor to
 B. B. Chemical Co., Boston, Mass., a corporation of Massachusetts

Application January 25, 1940; Serial No. 315,570

7 Claims. (Cl. 91—43)

This invention relates to coating apparatus and is herein illustrated as embodied in a machine such as that disclosed in Letters Patent of the United States 2,100,341, granted November 30, 1937, upon the application of Wilbur L. MacKenzie for applying a ribbon of cement to the margin of a shoe bottom.

It is an object of the present invention to provide an articulated nozzle suitable for use in machines of the character above referred to, which will apply an even ribbon of cement regardless of irregularities on the shoe bottom and which will not leak at its joints. Accordingly, the invention provides a nozzle comprising a supporting member having a supply passage, and a plurality of delivery tubes provided with passageways, these tubes being arranged around and connected to the supporting member at different points thereabout by ball and socket connections and having aligned outlets closely associated to apply a ribbon of cement. Passageways through these ball and socket connections join the supply passage of the supporting member and the passageways in the tubes.

The invention will be better understood when considered with relation to the accompanying drawing, in which

Fig. 1 is an end elevation of the head of a machine of the type shown in the MacKenzie patent above referred to, to which is applied my improved nozzle;

Fig. 2 is a cross section of the nozzle along the line II—II of Fig. 1;

Fig. 3 is a perspective view of the nozzle; and

Fig. 4 is a view of the ends of the delivery tubes showing the outlet openings therein.

As in machines of the type illustrated in the patent above referred to and used for cementing shoe bottoms to which soles are to be attached by cement, a rubber-tired feed wheel 10 for engaging the side of an inverted shoe is journaled in a member 12 supported between the sides of a frame 14. On this frame there is an adjustable nozzle carrier 16 having an outwardly extending rod 18 to which a nozzle arm 20 is secured by means of a clamp 22. Attached to the lower end of this arm 20 is a block 24 having a supply passage 26 to which cement under pressure is conducted from a receptacle (not shown) by means of a pipe 28.

In order that the operator may readily shut off the supply of cement as each piece of work is withdrawn from the machine and turn it on again for the next piece of work, a valve rod 30 is slidably mounted in the passage 26 and extends

far enough into said passage, as determined by a limit nut 32, to cut off the supply of cement delivered through the pipe 28. A bracket 34 attached to the nozzle-supporting arm 20 is apertured at 36 to guide the upper end of the rod 30 and to serve as an abutment for a compression spring 38 surrounding that rod and bearing against a collar 40 thereon. This spring moves the valve rod to the closed position shown in Fig. 1. When the operator wishes to open the valve, he turns a shaft 42 by means of a connection to a treadle (not shown). This shaft is journaled in the arm 20 and is provided with a cam 44 adapted to engage the under side of a lever 46. The lever 46 is pivoted at 48 on the bracket 34 and at its outer end 49 surrounds the valve rod 30 and underlies the collar 40.

The nozzle itself is built around a block or supporting member 50 secured to a neck 52 on the block 24 by a set screw 54. As shown in Fig. 2, the forward portion 56 of the block 50 is drilled to form four hemispherical recesses into which are inserted the hemispherical ends 58 of hubs 60 which carry delivery tubes 62, 64. The ball and socket joint thus formed insures a tight connection between the hub and the block through which no coating material can leak, even though manufacturing errors result in imperfect alignment of the axis of the hub and of the recess. The recesses for the hubs are spaced at intervals about the sides of the forward portion of the block 56 so as to leave ample room for the hubs and the tubes to pivot in their sockets, the outer tubes 62 being connected to the opposite sides of the lower portion of the block and the inner tubes 64 being connected to the opposite sides of the upper portion of the block. The inner tubes are bent slightly so that the ends of all the tubes, which are squared to permit them to be brought closer together, will lie in approximately the same plane and with the outlet openings aligned and arranged contiguously to apply merging stripes forming a ribbon of cement.

The supply passage 26 is connected to passageways 66 (Fig. 1) in the delivery tubes by passages 68 extending through the bottoms of the sockets and through the hemispherical portions of the hubs to the passageways in the tubes. The passageways in the tubes are sufficiently small so that, when cement is not being pumped through them, capillary action will prevent them from drooling. The outlet openings 70 of the tubes, however, are larger than the main portion of the passageways to simplify cleaning of the passageways and also to reduce the tendency of the tubes

to apply the cement in a series of strings. It is to be noted (Fig. 4), that the outlet openings of the outer tubes 62 are slightly smaller than the outlet openings of the inner tubes. By such an arrangement, a more even ribbon of cement is obtained and, in addition, the relative smallness of the openings in the two outer tubes assists fins 72 in confining the margins of the ribbon to proper bounds.

To hold the hubs 60 of the delivery tubes tightly against the forward portion 56 of the block and thus keep the ball and socket connections tightly sealed against leakage, there are provided two plates 74, preferably of spring metal, which are secured to the sides of the supporting member 50 by screws 76. Ears 78 on the spring plate 74 are bored to receive pins 80 integral with the hubs so that the tubes may swivel about the axis of the pins 80 but cannot move sideways. Downward movement of the tubes is limited by a plate 82 secured on the bottom of the forward portion 56 of the supporting member by a screw 84. A number of pins 86 are fastened to the forward end of this plate, one for each of the delivery tubes, so that when the latter move downwardly they will strike these abutment pins. Two pins 88 are also secured to the bottom plate 82 to provide some support against lateral bending of the outer delivery tubes by the work.

The tubes are yieldably held against the abutment pins 86 by a series of small leaf springs 90 clamped to the supporting member 50 by a notched plate 92 held in place by nuts 94. Pins 96 are secured to the forward ends of the leaf springs 90 and the end of each pin enters a recess formed in an upstanding neck 98 integral with each of the delivery tubes. Thus, the tubes are held in their lowest position by the leaf springs but may yield upwardly when they encounter an irregularity in the work piece beneath them. This arrangement is not claimed herein, however, since it forms part of the subject-matter of an application Serial No. 312,539, filed January 5, 1940, in my name.

The operation of the nozzle is believed to be self-explanatory. When the operator depresses the treadle to move the valve rod 30, the cement enters the supply passage 26 and passes through the hubs into the delivery tubes and thence through the contiguous outlet openings 70 onto the work. It will be found that a nozzle of this type will apply an even ribbon of cement along the margin of a shoe bottom, regardless of its irregularities and regardless of the marginal contour of the shoe.

Having thus described my invention, what I claim as new and desire to secure by Letters Patent of the United States is:

1. In an apparatus for extruding a stripe of viscous coating material on an irregular surface, a nozzle comprising a supporting block having a supply passage centrally located therein, a plurality of delivery tubes provided with passageways, two of said tubes being articulately connected to opposite sides of one portion of said supporting block at one side of said supply passage and other of said tubes being articulately connected to other portions of said supporting block at the other side of said supply passage, and passages through the points of connection joining said supply passage and the passageways in said tubes.

2. In an apparatus for extruding a stripe of viscous material on an irregular surface, a flexible nozzle comprising a supporting member hav-

ing a supply passage, a plurality of delivery tubes provided with passageways and articulately connected to said supporting member at points spaced heightwise thereof for free heightwise movement, and means for holding said tubes against a piece of work presented thereto, said tubes having aligned applying ends provided with outlet openings arranged contiguously to apply a stripe of coating material to a work piece moved progressively past the nozzle, said supply passage and the passageways in said tubes being interconnected.

3. In an apparatus for extruding a stripe of viscous coating material on an irregular surface, a nozzle comprising a supporting member having a supply passage, a plurality of delivery tubes provided with passageways and joined by freely turning ball-and-socket connections to opposite faces of said supporting member, said connections having passages interconnecting the supply passage with the passageways in the tubes, said delivery tubes having aligned applying ends provided with outlet openings arranged contiguously to apply a stripe of coating material to a work piece, and means for holding said tubes against a piece of work progressively presented thereto.

4. In an apparatus for extruding a stripe of viscous coating material on the irregular surface of a piece of work, a nozzle comprising a supporting member having a supply passage and provided with sockets opening outwardly and connected with said supply passage, and a plurality of delivery tubes yieldably held down in a predetermined position relatively to said supporting member and constructed and arranged for upward deflection by work presented thereto, said tubes having ball-shaped end portions freely tiltable in said sockets and provided with passageways opening through the ball-shaped portions and extending to outlet openings in the free ends of the tubes, said free ends having aligned ends provided with outlet openings arranged contiguously to apply a stripe of coating material to a work piece moved in contact with said ends.

5. In an apparatus for extruding a stripe of viscous coating material on an irregular surface, a nozzle comprising a supporting block, a supply passage centrally located therein, a plurality of delivery tubes provided with passageways and having hubs joined by ball and socket connections to said supporting block, two of said hubs being connected to opposite sides of one portion of said supporting block at one side of said supply passage and other of said hubs being connected to other portions of said supply block at another side of said supply passage, and means for connecting the supply passage to a source of supply of coating material.

6. In an apparatus for extruding a stripe of viscous coating material on an irregular surface, an articulated nozzle comprising a supporting member having a supply passage, a plurality of delivery tubes provided with passageways and having hemispherical hubs constructed and arranged to fit into complementary sockets spaced about said supporting member, yieldable members holding said hubs in engagement with said sockets, means for holding the delivery ends of said tubes in engagement with a piece of work presented thereto and passageways through said hubs connecting said supply passage and the passageways in said tubes, the outlets of said tubes being arranged contiguously to apply a

series of merging parallel stripes of coating material to a work piece.

7. In an apparatus for extruding a stripe of viscous coating material on an irregular surface, a nozzle comprising a supporting block having a supply passage, delivery tubes provided with passageways terminating in outlet openings at the lower ends of said tubes, said tubes being positioned in groups upon the opposite sides of said supporting block and communicating with said supply passage, said tubes being loosely pivotally connected to and removable individually from

said block, a support positioning said tubes in a position inclined downwardly from said supporting member, means for yieldably holding said tubes against said support and arranged to permit upward deflection of the outlet ends upon the presentation of a piece of work thereto prior to movement past the tubes, and individual yieldable means pressing each tube against said block to maintain the pivotal connection of said tubes with the supporting block.

RUSSELL K. NASH.
